BICYCLE CHANGE-SPEED CONTROL LEVER

Lucien Charles Hippolyte Juy, 75 Rue General-Fauconnet, Dijon, France

Filed May 15, 1967, Ser. No. 7,104

Claims priority, application France Jan. 21, 1967

Term of patent 14 years

(Cl. D90—1)

FIGURE 1 is a front elevation of a bicycle change-speed control lever showing my new design,

FIGURE 2 is a rear elevation corresponding to FIGURE 1 on the side including the bracket for mounting the control lever on the bicycle frame,

FIGURE 3 is an end elevation as seen from the right in FIGURE 1,

FIGURE 4 is an end elevation as seen from the left in FIGURE 1,

FIGURE 5 is a top plan view, and

FIGURE 6 is a bottom view.

I claim:

The ornamental design for a bicycle change-speed control lever, as shown and described.
